UNITED STATES PATENT OFFICE.

JOHN J. GEIGER AND LYMAN KNAPP, OF CLYDE, OHIO.

ROOFING.

SPECIFICATION forming part of Letters Patent No. 453,470, dated June 2, 1891.

Application filed January 17, 1891. Serial No. 378,149. (No model.)

To all whom it may concern:

Be it known that we, JOHN J. GEIGER and LYMAN KNAPP, of Clyde, in the county of Sandusky and State of Ohio, have invented 5 certain new and useful Improvements in Roofing; and we do hereby declare the following to be a full, clear, and exact description of the invention, such as will enable others skilled in the art to which it pertains to make and 10 use it, reference being had to the accompanying drawings, which form part of this specification.

Our invention relates to an improvement in roofing; and it consists in the combination of 15 a strip or piece which is formed from a single sheet of metal and is bent or doubled so as to form a double **T** with the sheets out of which the roof is formed, and which have their edges bent so as to fit in the sides of the 20 double **T** and a cap which is placed over the upper flanges of the double **T** and the roofing-plates, and then bent down, as will be more fully described hereinafter.

The object of our invention is to provide a 25 metallic roofing in which the parts are quickly and readily applied together, and then secured in position, without requiring the skilled labor which has usually to be employed in this connection.

30 Figure 1 is a detail view showing all of the parts of a portion of a roof ready to be put together. Fig. 2 is a similar view showing the same parts put together, but the cap-piece not bent over. Fig. 3 is a vertical section of 35 the parts when completed. Fig. 4 is a detail view of an end piece.

A represents a sheet of metal which has been bent so as to form a double **T**, and which is to be nailed directly upon the roof at its 40 lower edges. The sheets or plates B which form the roofing proper have their edges bent into a **U** shape, so as to fit within the flanges of the part A, and then the cap-piece C is applied over the upper edges of the double **T**

and the plates B, as shown, for the purpose of 45 securing the plates to the part A. As will be seen, the upturned edges of the sheets or plates B are made **U**-shaped, so that the upper edges D will extend horizontally outward directly under the top flanges a of the part A, so that 50 when the cap is applied the top flanges of the part A and the turned-out edges of the plates B will be secured together. The edges of the cap are then closed together, and the flanges inclosed in the cap are bent down, as shown, 55 so as to form a tight joint.

At the ends of the roof, instead of having the double-**T** pieces A, the flanged end pieces G are used, and which pieces have a flange H upon their inner sides about one-half way 60 down and two flanges a at their upper edges. Only one flange is formed at the center, because the sheets or plates B are applied only to the inner sides of the end pieces. A cap is then applied to the top flanges, which are then 65 turned down, as shown in Fig. 3.

As a sheet-metal roof constructed as here shown and described can be readily applied without the help of skilled labor, a great reduction in the cost of the roof is effected and 70 an absolutely tight joint without solder is made.

Having thus described our invention, we claim—

In a metallic roofing, the combination of the 75 double-**T** pieces, the roofing-plates having their outer edges made **U**-shaped, so as to fit in the sides of the double **T**'s, and the caps which secure the double **T**'s and the roofing-plates together, substantially as shown. 80

In testimony whereof we affix our signatures in presence of two witnesses.

JOHN J. GEIGER.
LYMAN KNAPP.
